INVENTOR
HAROLD FULTON

BY *William Bink*

ATTORNEY

UNITED STATES PATENT OFFICE.

HAROLD FULTON, OF ELYRIA, OHIO.

ARTICLE RETAINER.

Application filed June 21, 1920. Serial No. 390,552.

To all whom it may concern:

Be it known that I, HAROLD FULTON, a citizen of the United States, residing at Elyria, in the county of Lorain and State of Ohio, 5 have invented certain new and useful Improvements in an Article Retainer, of which the following is a specification.

This invention relates to an article retainer adapted to be pinned within the pocket of 10 an article of apparel and it consists in the novel features hereinafter described and claimed.

An object of the invention is to provide an article retainer of simple and durable 15 structure which may be conveniently used for securely holding articles, as for instance a pencil, scale and rule in the pocket, whereby the articles are held when the wearer of the article of apparel is in a stooping position and the articles are readily accessible 20 when they are required for use.

With these objects in view the retainer comprises a strip of metal bent or folded upon itself and being secured together at 25 its ends. The said strip so formed is provided at one end with a circular portion adapted to retain a pencil and with substantially parallel portions adapted to retain a rule or scale. Retaining tongues are struck 30 up from the body of the strip and are adapted to engage the articles when inserted in the retainer and hold them. Partitions are also struck up from the parallel portions and divide the space between them into compartments. 35 The upper edges of the strip are flared and the said flared portion may serve as a guide for directing the article into the retainer. A supporting pin is mounted upon one of the parallel portions and may be 40 passed through the material of the pocket and hold the retainer therein.

In the accompanying drawing:

Figure 1 is a side view of the article retainer.

Figure 2 is a top edge view of the same.

Figure 3 is a horizontal sectional view thereof cut on the line 3—3 of Figure 1.

Figure 4 is a transverse sectional view of the retainer cut on the line 4—4 of Figure 1 50 and showing the same applied to a pocket.

The article retainer comprises a metallic strip 1 which is bent or folded upon itself and when so formed is provided at one end with an enlarged circular portion 2 adapted 55 to receive and hold a pencil or similar article. The portions 3 are spaced from each

other and extend from the portion 2 in substantially parallel lines. The ends of the strip are overlapped and secured together by means of rivets 4 or other similar securing devices.

Partitions 5 are struck up from one of the side portions 3 and are inwardly disposed between the portions 3 and divide the space between the portions into compartments 65 adapted to receive and retain rules, scales or similar articles. Tongues 6 are also struck up from the body of the strip 1 and lie one in the circular portion 2 and one in each of said compartments.

A pin 7 is pivotally connected with one of the side portions 3 in a suitable manner and its free end portion may engage under a tongue provided upon the side portion in a manner similar to that of the pin of the 70 usual breast pin.

When applied to an article of apparel the retainer is located in the pocket thereof and the pin 7 is passed through the material of one side of the pocket and secured whereby 80 the retainer is held in an elevated position in the pocket and in the vicinity of the upper edge or mouth thereof. The strip 1 is provided at its upper edges with a flared portion 8 which may serve as a guide for directing 85 articles into the retainer when they are being inserted therein.

From the above description taken in conjunction with the accompanying drawing it will be seen that an article retainer of simple structure is provided and that the same will securely retain articles therein when the user is in a stooping posture and hence the articles are prevented from accidentally dropping from the retainer and are always 95 retained ready at hand for use.

Having described the invention what is claimed is:

As a new article of manufacture, an article retainer comprising a member formed 100 from a rectangular blank of sheet material of elongated form and uniform width and thickness throughout its length, said blank being bent on its central portion to form parallel side members connected at one end by 105 a loop portion forming a cylindrical pocket, the opposite ends of the side member being turned toward one another and connected, a plurality of inwardly directed partition members struck out from one side plate, a 110 plurality of spring clamping members between said partition members and struck

out from said first mentioned plate, said spring clamping members having portions depending into the spaces provided between said partition members to grip articles placed therein, a spring gripping member

5 struck out from one of said plates and extending into said cylindrical pocket to grip an article inserted therein, and means carried by one of said plates for attaching the article holder removably to an article of clothing.

In testimony whereof, I affix my signature.

HAROLD FULTON.
